UNITED STATES PATENT OFFICE.

WILLIAM R. BURROWS, OF NEWARK, NEW JERSEY, ASSIGNOR TO GENERAL ELECTRIC COMPANY, A CORPORATION OF NEW YORK.

MACHINE FOR MAKING INCANDESCENT LAMPS.

No. 884,568.

Specification of Letters Patent.

Patented April 14, 1908.

Application filed November 25, 1903. Serial No. 182,642.

To all whom it may concern:

Be it known that I, WILLIAM R. BURROWS, a citizen of the United States, residing at Newark, in the county of Essex and State of New Jersey, have invented certain new and useful Improvements in Machines for Making Incandescent Lamps, of which the following is a specification.

This invention relates to machines for use in the manufacture of incandescent lamps, and particularly small telephone lamps and fancy lamps for ornamental use.

The machine is especially adapted for shaping the bulb or sealing together by an all-glass joint the bulb and stem of these small lamps, but other uses of the machine will readily suggest themselves to those skilled in the art.

One feature of the machine is that the glass tubes or the bulb and stem are adjustably held on a rotatory frame at the focal point of a plurality of blow-pipe flames and connected by flexible tubes with parts on the frame which are in communication with a source of supply of compressed air. By this construction air under pressure may be admitted to the glass parts while rotating in a gas flame and when the rotation is arrested, but before the glass has cooled they may be adjusted relatively while still in connection with the source of air-pressure.

Another feature is that each of the pipes carrying the gaseous pressure to the machine is provided with a vent or leak-hole which reduces the pressure to practically that of the atmosphere but which can be closed by the operator entirely or to any desired degree to obtain a delicate regulation of the pressure within the glass parts. By this construction the work of shaping or joining together the glass parts can be done quickly and hence at small cost, the breakage is small, and no great degree of skill is required of the operator.

The novel features of my invention will be definitely indicated in the appended claims; the details of construction and the mode of operation will be better understood by reference to the accompanying drawings which show an embodiment of my invention and in which

Figure 1 is an elevation, and Fig. 2 a plan of my improved glass-working machine.

In the drawings, 1 indicates the base of the machine on which is a standard 2 carrying a

support near its lower end which is bifurcated and has hubs 3 3 formed on the ends of the bifurcated arms. Near the top of the standard is an arm 4 in the end of which is a bearing, and mounted to rotate in the bearing in arm 4 and in the hubs 3 3 is a frame consisting of a rod 5 connecting two arms 6 6 each of which has an opening near one end into which rod 5 extends and an opening through the arm at the other end. On the upper arm and registering with the opening therethrough is a hollow journal which coöperates with the bearing in arm 4; and fitting into the opening through the lower arm 6 is a short hollow shaft 7 which extends down through the hubs 3 3 and carries a pulley 8 between the hubs. A belt 9 connects this pulley with a pulley 10 loosely mounted on a shaft 11 which carries a pulley 12 and is driven by a belt running on pulley 12 from any suitable source of power. Pulley 10 is provided with a number of openings in one side, and a movable clutch-member 13, splined to shaft 11, carries a pin 14 which is adapted to enter one of the openings to lock shaft 11 into driving relation to the pulley. The clutch-member 13 is moved into or out of engagement with pulley 10 by a pedal controlled by the operator and connected to the clutch-member 13 by rods 15 and levers 16 as shown. The hollow shaft 7 carrying the pulley 8 is connected to a source of air-supply by a pipe 17 communicating with a connecting member 18 which is pressed upward into the hollow shaft by a spring 19 surrounding a stud on base 1. Connected to the upper end of the hollow shaft 7 by an air-tight joint is a flexible tube 20. A similar flexible tube 21 connects through the upper arm 6 and the hollow journal thereon with the bearing in arm 4 which is connected by a pipe 22 to the source of air-supply.

Extending upward from base 1 are two standards 23 carrying a ring 24 which is broken away in front to permit the operator to see the work and in which are two annular chambers, one connected to a source of gas-supply by a pipe 25 and the other connected to the source of air-supply by a pipe 26. Communicating with the gas chamber in the ring 24 are a number of burners 27 with which a number of blow-pipes 28 communicating with the air-chamber in the ring 24 coöperate to afford a plurality of blow-pipe flames converging upon a point in the

- axis of rotation of the frame. The pipes 25 and 26 which supply the gas and air to the ring 24 are provided with a valve 29 which is arranged to be opened and closed by a pedal 5 controlled by the operator and connected to the valve by a rod 30 and arm 31. Adjustably mounted on rod 5 are two spring clamps 32 which grip the glass parts and hold them in the axis of rotation of the frame. Also 10 adjustably mounted on rod 5 is a plate 33 which partially encircles the glass tube on which the flames are playing, to prevent the heat from spreading down the tube to any great extent.
- 15 The air-pipes 17 and 22 extend down to the operator's table and along it to a point within convenient reach of the operator, where each pipe is provided with a vent 34 through which the air escapes sufficiently to 20 reduce the pressure within tubes 20 and 21 to practically atmospheric pressure. The vents 34 may be closed entirely or to any desired extent by the operator to adjust the pressure of air within the tubes by placing 25 one finger over the vent.
- When the machine is used for sealing-in, the glass tube, in the end of which a bulb has been formed, is mounted on the rotatable frame with its end in the end of the flexible 30 tube 21 and the upper clamp 32 sprung onto the bulb to hold it in the proper position relatively to the blow-pipe flames. The tube on which a stem has been formed and a filament mounted is similarly inserted in the 35 flexible connection 20, raised to the proper position with the filament and part of the stem within the bulb, and held in place by the lower clamp 32. The operator then starts the rotation of the frame by pressing the 40 pedal connected by the rods 15 and levers 16 to the clutch-member 13, and thereby moving member 13 into engagement with pulley 10. She then presses the pedal connected to valve 29, opening the valve and permitting 45 the blow-pipe flames to play upon the edge of the bulb and the portion of the stem to which the bulb is to be joined. When the glass has become softened, the operator raises the pressure within the stem by partially 50 closing the vent 34 in pipe 17 with her finger. This is best done by resting the hand on the table and tapping lightly with one finger on the pipe about the vent so that the escape of air through the vent is checked 55 only momentarily and the operator can see the effect of each closure. By closing the vent 34 more or less or for greater or less periods, the pressure within the stem can be regulated exactly as desired. In this way 60 the stem is expanded at the point where the joint is to be made and, at the same time, the edge of the bulb, under the influence of the blow-pipe flames, is softened and falls in around the expanded portion of the stem and 65 the two join and become thoroughly weld-
- ed together. The operator then partially closes the vent in the pipe 22 in the same way, thereby increasing the pressure within the bulb and properly shaping the joint. Then by releasing the pedals the rotation of 70 the frame is stopped and the flames are cut down. Before the glass has become cooled, the operator by drawing the tubes connected to the bulb and stem apart, the tubes sliding through the spring clamps 32, and by adjusting the pressure within the tubes, trues 75 up the parts and gives them the exact shape desired. The vents 34 in the air-supply pipe afford means for adjusting the air pressure within the tubes with such delicacy that unskilled operators quickly become expert at 80 making the joints and shaping the parts, and the output of the machine is large and the product uniform.
- I have described my invention with reference 85 to sealing the stem of a lamp into the bulb, but I do not wish to be understood as limited to any particular use or to the exact construction shown. The machine is equally well adapted for forming lamp bulbs from a 90 straight tube. The tube may be placed in the clamps 32 with the air-tubes 20 and 21 connected at its ends. The frame is then rotated and the burners turned up as before, and when the glass is softened the tube may 95 be expanded by regulating the air pressure within the tube and extended by drawing the ends through the spring clamps 32, as above described, to form in the tube a bulb of any desired shape or size. In addition to these 100 uses, others will be evident to those skilled in the art of forming articles of glass.
- What I claim as new and desire to secure by Letters Patent of the United States, is,
1. In a sealing-in machine, supports for holding the bulb and stem in alinement with each other and permitting relative adjustment thereof, means to heat the glass, and separate connections for admitting gaseous pressure to the bulb and stem respectively 105 in any adjusted position.
  2. In a sealing-in machine, supports for holding the bulb and stem in alinement with each other and permitting relative adjustment thereof, means to heat the glass, and 110 means for regulating the pressure within the bulb and stem independently of each other in any adjusted position.
  3. In a sealing-in machine, a rotatable frame, means carried thereby for supporting 115 the bulb and stem and permitting relative adjustment thereof, burners for heating the glass, and means for admitting gaseous pressure to the bulb and stem independently of each other while rotating in any adjusted 120 position.
  4. In a sealing-in machine, a rotatable frame, means carried thereby for supporting the bulb and stem and permitting relative adjustment thereof, burners for heating the 125 130

- glass, and means for regulating the pressure within the bulb and stem independently of each other while rotating in any adjusted position.
5. In a glass-working machine, a frame, a tube-holder carried thereby arranged to permit adjustment of a tube held therein, a plurality of burners, connections for carrying gaseous pressure to the frame, and flexible tubes secured at one end to the frame in communication with said connections and adapted to have their other ends fitted over tubes held in said holder.
6. A glass-working machine comprising a frame, two tube-holders carried thereby arranged to permit adjustment toward and away from each other, means for rotating the frame, a plurality of burners, connections for carrying gaseous pressure to the frame while rotating, and flexible tubes secured at one end to the frame in communication with said connections and adapted to be secured at their other ends to tubes held in said holders.
15. 7. In a glass-working machine, means for supporting a tube, and a pipe for carrying gaseous pressure to a tube held in said supporting means, provided with a vent adapted to be closed by the operator with one finger.
20. 8. In a glass-working machine, a table, a frame mounted thereon, a support for tubes carried by the frame, and pipes for carrying gaseous pressure to the tubes held in said support, said pipes extending in proximity to the top of the table and having vents therein at a point near the top of the table.
25. 9. In a glass-working machine, a support for a tube, and a pipe connected to a source of gaseous pressure and arranged to be connected to a tube held in said support, said pipe being provided with a vent arranged to reduce the pressure in the pipe to practically that of the atmosphere and adapted to be closed by the operator with one finger.
30. 10. A glass-working machine comprising a frame, a tube-holder carried thereby arranged to permit adjustment of a tube held therein, a plurality of burners, pipes for carrying gaseous pressure to the frame, said pipes being provided with vents arranged to be closed by a finger of the operator, and flexible tubes secured at one end to the frame in communication with said pipes.
35. 11. In a sealing-in machine, supports for the bulb and stem, means for rotating said supports, burners to heat the glass, and means for regulating the pressure within the bulb and stem, comprising air-pipes communicating with the bulb and stem and each provided with a vent arranged to be closed by a finger of the operator.
40. 12. In a sealing-in machine, supports for holding the bulb and stem in alinement with each other and permitting relative adjustment thereof, means to heat the glass, and means for regulating the pressure within the bulb and stem in any adjusted position, comprising air-pipes communicating with the bulb and stem and each provided with a vent arranged to be closed by a finger of the operator.
45. 13. A machine for forming incandescent lamps, comprising a support for the lamp parts, means for softening the glass, a source of gaseous pressure connected with the lamp, and a normally-open leak opening in said connection at a point near the lamp to cut down the pressure, said leak-opening being adapted to be closed intermittently by a finger of the operator to graduate the pressure.
50. 14. In a glass working machine, the combination with a tubular support for the glass, of a source of compressed air connected to the interior of said support, and a regulable vent to the atmosphere for controlling the pressure of air in said support.
- In witness whereof, I have hereunto set my hand this 23d day of November, 1903.
